UNITED STATES PATENT OFFICE

2,360,785

SAFETY RAZOR FOR DRY SHAVING

Fred J. Mehl, Wichita, Kans., assignor of twenty-five per cent to Ulysses G. Charles and fifty per cent to Jay Bergman, both of Wichita, Kans.

Application July 21, 1941, Serial No. 403,305

2 Claims. (Cl. 30—43)

The invention herein disclosed relates to a safety razor for dry shaving, and has for its principal object a brushing means to direct beard or hair in contact with the edge of a cutting blade, and causing the beard to be severed at the instant of contact.

A further object of this invention is to provide duplex rotors oppositely rotating to convey the beard against the razor's line of movement, whereby a slanting position of the razor's casing as a whole will determine which blade edge will be engaged. However, two cutting edges may be engaged by pressing the head of the razor on the face at right angles to its surface; in other words, an advancing edge is provided for reciprocating movement of the cutting head.

A still further object of this invention is to provide for oppositely disposed cutting edges through the medium of a pair of blades that are interchangeable or replaceably arranged, and being carried by a rockable support, in which instance, one rotor is provided and means to reverse its direction of rotation, whereby the blade support will rock to a reversed position, in which instance, the blade that was idle will become active as the face of the rotor will conduct the beard toward the cutting edge, and vice versa when the direction of rotation of the rotor is reversed.

A still further object of this invention is to provide a series of diamond forms positioned in spaced relation and uniformly distributed on the periphery of the rotor, whereby the body of the diamond forms will function as a guard while the vertically disposed advancing edges of the diamonds will meet the edge of the blade slantingly for a shearing cut, and the grooves between the diamond forms will receive the beard therein as severed by the blade and convey the severed beard inward of the head.

A still further object of this invention is to provide a cutting blade and a rotor for long duration, as a light contact of the rotor and blade will tend to sharpen the blade, and each being of highly tempered steel to maintain a polish and keen cutting edges.

These and other objects will hereinafter be more fully described, reference being had to the accompanying drawing forming a part of this specification, and in which like characters will apply to like parts in the different views.

Referring to the drawing:

Fig. 1 represents a pair of rotors, spaced apart with a double edged blade positioned to engage each rotor with its respective edge of the blade.

Fig. 2 is a plan view of Fig. 1, parts removed for convenience of illustration.

Fig. 3 is a reduced side view of the razor mechanism as a whole.

Fig. 4 is a sectional view through the casing, taken on line 4—4 in Fig. 2.

Fig. 5 represents a pair of rotors in close relation, and a cutting blade for each rotor.

Fig. 6 is a fragmentary plan view of Fig. 5.

Fig. 7 is an end view of the head, the casing fragmentarily shown.

Fig. 8 represents a single rotor in cross section and a pair of blades rockably arranged and positioned at one side of the rotor with respect to a vertical diametrical axis of the rotor.

Fig. 9 is a fragmentary plan view of Fig. 8.

Fig. 10 is an end elevation of Fig. 8, illustrating the rocking movement of the blades to the opposite side of the rotor to that shown in Fig. 8 as shown by dotted lines.

Fig. 11 is a plan view similar to Fig. 9 but having a handle axial with the rotor.

Fig. 12 is a sectional view taken on line 12—12 in Fig. 11.

Fig. 13 is an enlarged view to illustrate the principle of the diamond forms with respect to the cutting edge of the razor blade.

The invention herein disclosed consists of rotors 1 and 1' appropriately journaled in a casing 2 and cutting blades 3 and 3' carried by the casing in working relation to the rotors by a means later described, the rotors having in spaced relation a plurality of diamond forms A distributed on the periphery of the rotor body 35 and being formed by grooves B diagonally positioned on the periphery of the rotor body, the grooves extending from end to end of the rotor, the angle of the grooves being sufficient to elongate the diamonds, whereby the acute angles

40 are longitudinal of the rotors, while the obtuse angles are transverse with respect to the rotor. However, the contour walls of the diamonds are radially positioned with respect to the rotor to provide a shoulder and a sharp cutting edge adjacent the outer face of each diamond form.

Being so arranged, the obtuse points of the diamonds will move beneath the cutting edge as the rotor turns, and from thence a shearing cut is had to each acute point of the said diamond forms in their consecutive order as the rotor turns, the grooves being another means to receive the beard of the face and being severed by the shearing contact above described. Furthermore, the advancing edges of the diamonds will brush the beard extension toward the edge of the

blade as the head of the razor is moved over the face, whereby the said beard will enter the grooves at the instant of cutting, and from thence being conveyed inward of the razor head and centrifugally discharged into an appropriate chamber for future removal therefrom.

It will be seen that the interlapping of the diamond edges is a means to guard the edges of the blades from contact with the edge of the diamond forms, and furthermore the outer face of the diamond forms, being smooth and highly polished, will function as a safety guard to avoid cutting the face during the process of shaving. The outer surface of the said diamond forms, being so finished, will further function as an abrasive sharpening means for the edge of the blade as the same is adapted to lightly contact therewith as the rotor turns.

The blades as shown in Figs. 2 and 6 may be secured to their respective casing by seating the ends of the blades on the casing, and being secured thereto by the lip C of a latch 4 that is hingedly connected at its lower extremity to the casing as at D, the latch lip adapted to lap to and from engagement with their respective ends of the blades and being tensioned to engagement with the blades by springs 5 wound on a hinged pin 6, one end of the spring lying on the latch body while the other end engages on the casing as shown in Fig. 7. Being so arranged, the blades are easily removed, replaced, and bound firmly in place.

In Fig. 1 is shown a single blade having two cutting edges, each being positioned in working relation to its respective rotor adapted to turn toward its respective cutting edge of the blade as indicated by the arrows; said blade having convex sides with respect to cross section will function as a guard in conjunction with the peripheral faces of the rotors to avoid cutting the face while shaving. The blade, being so formed, is invertible and reversible with respect to its ends, and the shaving movement may be in either direction with respect to the cutting edges of the blade.

In Fig. 5, it will be seen that a pair of rotors in close relation is means to position a pair of cutting blades oppositely, there being one for each rotor, said blades each having one cutting edge and the sides of the blade being straight, the edges confronting each other and bearing on their respective rotors; being so arranged, the blades will shave simultaneously as the rotors rotate toward their respective blade edges as shown by the arrows. However, with respect to shaving, the razor head may be moved reciprocatingly or in either direction so that a cutting edge will be in advance of its respective movement.

In Fig. 8 is shown a single rotor 7 having a greater diameter than the rotors previously described, but having a similar peripheral arrangement with respect to the diamond forms, said rotor being journaled in a casing 8 with power means to turn the same hereinafter described. It will be seen that the said rotor is equipped with blades 3 that are similar to the blades shown in Fig. 5, said blades being removably attached to their respective sides of a supporting element 9 so that the edge of each blade will be in contact or in working relation with the periphery of the rotor. The said support has secured to each end thereof a plate 10 that is axially truncated with the rotor through the medium of a pin 11 secured to the ends of the casing, where-

5 by the support is adapted to rock from side to side of the rotor as shown by whole lines and dotted lines E and being stopped in either position by detents 12 that are secured to the casing whereby the blades selectively may be brought to shaving engagement with the rotor, and furthermore the said rotor, being reversible with respect to rotation, is automatic means to rock the blade support with its direction of rotation, whereby either blade may be selectively positioned to shave.

In Fig. 4 is shown a method of reversing and driving a rotor as follows: Positioned on each end of the rotor is a gear 13 and being in mesh with gears 14 respectively, last said gears being secured to a shaft 15 that is journaled in the casing, said shaft having a friction spool 16 secured to the center thereof and adapted to slide longitudinally on the shaft and rotatable therewith, there being a pin 17 secured to the shaft and adapted to engage in a slot 18 extending through the side of the spool body to permit sliding movement thereof, and the said spool having a coil spring 19 wound on the shaft to engage with each end of the spool as flexible shifting means therefor. To shift the spool, there is arranged a yoke 20 having a right angle bend at each end thereof as at F, the latter each being bifurcated to straddle the shaft and to engage on their respective end of the spring. Said yoke has a knobbed finger 21 laterally extending outward and near the center thereof, the finger to engage through a slot 22 in the casing, the slot having an upturned opening G 20 on each end thereof to function as a detent for the knobbed finger by rocking said knobbed finger upward therein to retain the spool against retraction. The purpose of the shift is to reverse the revolving movement of the shaft, which 25 in turn reverses the rotation of the rotor. This function applies more directly to the rotor in Fig. 8, the reverse movement being through the engagement of a friction bevel pulley 23 when brought to engagement with either beveled end 30 as at J of the spool, said pulley being secured to the end of a driveshaft 24 that is motor-driven (the motor not shown in the drawing but positioned in the casing).

It will be seen that the driving mechanism 35 applies also to the rotors shown in Fig. 5, in which instance the gears on the ends of one of the rotors are in mesh with their respective gears 14 while the other rotor is frictionally driven by the first said rotor.

55 In the event of spacing the rotors apart as shown in Fig. 1, the driving mechanism is arranged to drive its respective rotor by gear 14 as shown by dotted lines, engaging therewith, while the other rotor is turned by an idle gear 25 in 60 mesh with its respective end gear 13 and with gear 14.

It will also be seen that the rotor as disclosed 65 in Fig. 8 may be driven direct by axial engagement of a motor shaft 26, the motor not being shown but positioned in the shell of a handle 27 that is secured to the head casing of the rotor, in which instance the motor may be of a reversing type, or a spring actuation may be provided, the latter also excluded from the drawing. However, the handle and the rotor being aligned axially, will function equally as well as in the process of shaving heretofore described, and such other modifications may be made as lie within the scope of the appended claims.

70 Having fully described my invention what I

claim as new and desire to secure by Letters Patent is:

1. In a safety razor for dry shaving, a pair of cylindrical rotors journalled in a casing in parallelism and frictionally engaging with each other, whereby one rotor will drive the other, and an edged cutting blade for each rotor secured to the casing, each rotor being grooved in two directions to provide series of elongated diamond shaped portions, said portions being evenly spaced longitudinally and peripherally of the cylindrical rotors, the longer axis of the diamond shaped portions running longitudinally of the rotor the slanting sides of said portions providing cutting edges which shearingly engage with the cutting edge of the blades, the blades engaging tangentially on the periphery of their respective rotors.

2. In a safety razor for dry shaving, a casing

comprised of two ends and four side walls, one end being open, a pair of rotors journalled in the open end of the casing and in parallelism, a peripheral portion of each rotor being outwardly protruded from the casing, the rotors having cutting edges and engaging each other peripherally and blades respectively having edges which respectively tangentially engage the rotors, means formed on each rotor by a series of slanting grooves in spaced relation peripherally, and a portion of the grooves oppositely slanting and crossing each other whereby the ungrooved portion of the rotors' periphery will slantingly engage with the cutting edges of the blades in opposite direction from a point of approach of the said means whereby a shearing cut for a beard is had as a rotor turns.

FRED J. MEHL.
